UNITED STATES PATENT OFFICE.

MAX ABRAMCHIK, OF CONEY ISLAND, NEW YORK.

METHOD OF DRYING MACARONI, SPAGHETTI, AND LIKE DOUGH PRODUCTS.

Application filed December 1, 1925. Serial No. 72,443.

My invention relates to a new and improved apparatus for drying spaghetti, macaroni, noodles and similar foods.

One of the objects of my invention is to devise a mechanism which will cause the long straight sticks of macaroni, spaghetti and similar foods to dry without altering their shape, as it is desirable that such foods should reach the consumer in the form of long straight sticks.

Another object of my invention is to devise a mechanism which can be regulated with great ease and efficiency.

Another object of my invention is to devise a mechanism of this character which will enable a forced circulation of air to be efficiently employed so as to minimize the time during which the drying operation takes place.

Other objects of my invention will be set forth in the following description and drawings which illustrate a preferred embodiment thereof, it being understood that the above general statement of the objects of my invention is intended merely to generally illustrate the same and not to limit it in any manner.

Fig. 1 is a sectional view partially in elevation.

Fig. 2 is a section on the line 2—2 of Fig. 1.

Fig. 3 is an elevation illustrating another embodiment of my invention.

Fig. 4 is a section on the line 4—4 of Fig. 3.

In drying noodles and particularly spaghetti and macaroni, it is necessary to conduct the operation with great care. The operation is not merely a drying one, as it is believed that certain chemical changes take place during the evaporation of the water in the dough. If these chemical changes are not carefully regulated, then the dried food is so brittle that it crumbles into a powder when it is handled, which of course is highly objectionable.

It has heretofore been customary to hang the food material for a long period of time in the open air. This took a great deal of time and furthermore, for sanitary reasons, it is desirable to minimize the length of time of the drying operation.

It has also been suggested to dry the food materials by means of air currents, but pre-

vious attempts have not resulted in producing long straight sticks of properly dried macaroni, spaghetti or the like.

According to the embodiment shown in Figs. 1 and 2, a chamber having walls 10 is provided and this chamber is provided with a series of racks 11 upon which the spaghetti, macaroni N or the like can be hung. A central hollow shaft 12 provided with a bottom bearing portion 14 is provided and this bearing portion 14 rests upon a suitable pedestal by means of intermediate ball bearings 17. The base of this pedestal is connected to a suitable foundation by means of bolts 18.

The hollow shaft 12 is provided with a series of fan blades 19 which are adapted to cause a current of air to be driven downwardly. Hence, a central descending column of air is produced in the drying chamber and this column of air does not directly flow over the strings of spaghetti, macaroni or the like. However, the moisture absorbed by the air in direct contact with the dough product can diffuse into the central space or zone of the drying chamber and be carried off by the descending column of air.

As shown in Fig. 1 the air which is driven downwardly by the blades 19 enters the hollow bearing portion 14 through the opening 16. This air then passes upwardly into the bottom inlet 15 and then into the bottom 13 of the shaft 12.

This prevents the downward current of air from spreading out laterally in a direction away from the central shaft 12. If the air were thus allowed to spread out laterally, it would then tend to flow upwardly in the space or zone in which the products are located, so that these products would be subjected to the drying action of a substantial and upwardly directed current of air, which I desire to avoid.

Hence, the long straight sticks of moist macaroni, spaghetti and the like are shielded from contact with any powerful air current. Also, if any flow of air is produced in the lateral zone of the drying chamber, that is, the zone in which the dough products are located, such air currents are downward.

A heater of any ordinary type may be installed in the drying chamber 10 and I prefer that this heater, if used, should be

located adjacent the bottom of the shutter 12. Such a heater is not necessary if it is desired to dry macaroni and spaghetti. However, if it is desired to dry short 6 noodles which are placed within the drying chamber in a series of piled up trays or the like, then it is preferable to have a heater H located at the bottom of the chamber.

- 10 As clearly shown in Fig. 1, the top of the hollow shaft 12 has a series of openings 20 and the shaft passes through a sleeve or extension of the conduit 21 to which the casing 22 of an exhaust fan is connected. 15 This exhaust fan has a shaft to which a pulley 23 is connected and this pulley 23 is driven by means of the belt 24. The belt 24 is connected to a pulley of the hollow shaft 12 and the hollow shaft 12 is driven 20 by means of a belt 25 which is connected to a pulley 27 of the shaft of the motor 26. The outlet end of the casing of the exhaust fan may be external to the chamber 10, so that a regulated amount of air can be forced 25 out of the chamber without producing any upward air currents.

A window 31 having an adjustable shutter of any ordinary type is provided so as to admit fresh air into the apparatus. The 30 use of the exhaust fan is only necessary where it is desired to more positively regulate the amount of fresh air entering through the window 31, independent of the action of the fan blades 19.

- 35 As clearly shown in Fig. 2, the chamber is provided with sliding doors 28 which may be opened in order to place the material within the chamber 10 or to take it out after the drying operation has been 40 completed.

However, it is not necessary that the doors 28 should be left open while the material is being dried, although this may be done if desired.

- 45 It is obvious that even if the doors 28 are left slightly open while the drying operation is being conducted, that the dough food will be dried by a descending current of air.

- 50 By locating the driving mechanism and the blower at the top of the apparatus, inspection and repair thereof is very much facilitated.

In the embodiment shown in Figs. 3 and 55 4, the shaft 12 is still driven by means of the belt 25 which passes over the shaft of the motor 26. The blades 19 still act to drive the air downwardly in the chamber 10. In this instance, however, a suction blower 50 29 is provided, the shaft 30 thereof being operated by means of a belt 24. Windows 31 are provided at opposite corners of the device, and these windows are provided with adjustable shutters so as to regulate 65 the flow of air.

In this embodiment the outlet of the suction devices 29 passes through one of the walls of the chamber 10. This outlet cannot be seen in Fig. 3 because it is hidden by the base 29' of the member 29.

70

In this embodiment a heater might be located, if desired, in any convenient part of the chamber 10, preferably at the bottom thereof. Since the suction blower 29 is located at the bottom of the chamber, 75 a downward current of air is produced, as in the embodiment before mentioned.

If desired, in the embodiment shown in Figs. 3 and 4, the blades 19 could be so mounted as to cause the air in the center 80 of the chamber to be forced upwardly, thus insuring a downward circulation of the air at those points of the chamber in which the spaghetti, macaroni or the like is located.

Practical experience has shown that by 85 using this method of drying the doughy materials that greater rapidity of operation is secured with much less care on the part of the operator. In drying operations as heretofore conducted by means of a forced 90 circulation of air, it was necessary to care- fully regulate the speed of the drying operation at various stages thereof and constant attention on the part of the operator was necessary. It was necessary to open 95 or close the sliding doors to a greater or less extent at various stages of the drying operation, and to generally conduct the method in such a manner that really precise regulation was not possible.

100

According to my method, the regulation can be very readily and efficiently accomplished at all times.

I have shown a preferred embodiment of my invention, but it is clear that numerous 105 changes and omissions could be made without departing from its spirit.

I claim:—

1. A method of drying spaghetti, macaroni and like dough products which consists in arranging said dough products in a substantially enclosed drying chamber in a lateral zone around a central zone which is free from said products, and forcing an air current downwardly through said central zone, while causing the downwardly directed air current to move away from said dough products in a path spaced from the zone in which said dough products are located, the moisture in said lateral zone being free to diffuse towards and into said central zone.

110

2. A method of drying spaghetti, macaroni and like dough products which consists in arranging said dough products in a substantially enclosed drying chamber in a lateral zone around a central zone which is free from said products, and forcing an air current downwardly through said central zone, while causing the downwardly 115

directed air current to move away from said dough products in a path spaced from the zone in which said dough products are located, while simultaneously exhausting air 5 from the central portion of the bottom of the drying chamber to cause the downwardly directed air current to move in the direction of the exhaust, the moisture in said lateral zone being free to diffuse towards 10 and into said central zone.

3. An apparatus for drying macaroni, spaghetti and like dough products comprising a drying chamber having an inlet at the upper part thereof, a vertical shaft located 15 in said chamber and around which the supports for said dough products can be arranged, the said shaft having fan blades connected thereto, and means adapted to 20 actuate said shaft to cause said fan blades to drive the air in said chamber downwardly, the moisture in said lateral zone being

free to diffuse towards and into said central zone.

4. An apparatus for drying macaroni, spaghetti and like dough products comprising a drying chamber having an inlet at the upper part thereof, a vertical shaft located 25 in said chamber and around which the supports for said dough products can be arranged, the said shaft having fan blades 30 connected thereto, and means adapted to actuate said shaft to cause said fan blades to drive the air in said chamber downwardly, said shaft being hollow and having inlet openings at the bottom thereof and outlet openings at the top thereof, and exhaust means associated with said outlet openings, the moisture in said lateral zone being free 35 to diffuse towards and into said central zone.

In testimony whereof I affix my signature.

MAX ABRAMCHIK.
